UNITED STATES PATENT OFFICE.

CHARLES A. LUCE, OF MANCHESTER, NEW HAMPSHIRE.

FIRE-ESCAPE.

SPECIFICATION forming part of Letters Patent No. 400,779, dated April 2, 1889.

Application filed April 30, 1888. Serial No. 272,246. (No model.)

To all whom it may concern:

Be it known that I, CHARLES A. LUCE, of Manchester, in the county of Hillsborough and State of New Hampshire, have invented 5 certain new and useful Improvements in Fire-Escapes, of which the following is a specification.

This invention pertains to certain new and useful improvements in fire-escapes, having 10 for its object the provision of a new and improved highly-efficient device of this class, that is designed to be secured to the front of a building as a permanent fixture or part thereof, and one that will not be unsightly in 15 appearance.

I am also enabled by my invention to carry 20 firemen or hose, or firemen with hose, to windows or parts of a building that could not be reached by a ladder, or by a ladder reached 25 as readily as by my invention.

Reference is made to the accompanying drawings, and to the letters of reference marked thereon, forming a part of this specification, of which drawings—

25 Figure 1 represents the side or end of a building having a part of my invention affixed to the building as a permanent part thereof. Fig. 2 is a view similar to Fig. 1, showing the manner of applying and using the "escape" 30 proper. Fig. 3 is a vertical sectional view of that portion of the invention that is adapted to be applied to a building as a permanent part thereof. Fig. 4 is a detail view showing the manner of applying and using the escape 35 proper.

The same letters of reference designate the same parts in all of the views.

In the drawings, let *a* designate the side or end of a building to which it is desired to apply 40 my improved fire-escape. To the wall or other secure and substantial part of the building, and at a point near the roof, or the highest point that it is desired to reach by the escape, I secure any suitable bearing for the 45 journals of sheaves or pulleys *b*. In the present example I have shown the supports for the sheaves or pulleys *b* as consisting of a base-plate, *c*, provided with the journal-bearing *d*, and housing-plate *e*, provided with the journal-bearing *f*, the base-plate *c* being secured to the sides or walls of the building *a* by means

of bolts *g*. At a point below the pulleys *b*, and preferably near the ground or sidewalk, I secure suitable supports for pulleys or sheaves *h*, preferably swiveling said pulley-support, so that the pulley may be turned to any desired position. I have herein shown a base-plate, *i*, as secured to the building *a* by means of bolts *j*, upon which base-plate *i* the pulley-support *k* is swiveled, as shown most 55 clearly in Fig. 3. Over pulleys or sheaves *b* and *h*, I pass an endless chain or rope, *l*, provided with hooks *m*, adapted to receive loops formed in or rings attached to the ends of a rope, chain, or cable, *n*, so that one end of 60 said rope *n* may be carried up over one pulley *b* and down about and under its associate pulley *h*, and the other end of said rope is carried up over the other pulley *b* and down and about its associate pulley *h*. The rope 65 or chain *n* is provided at a central point with an escape car or vehicle, *o*, which may be of any suitable form and composed of any suitable material. With this construction and arrangement of means it will be seen that by 70 drawing on the ends of the rope or chain *n* the portion of the latter intermediate of the sheaves or pulleys *b*, and to which the escape-car *o* is attached, may be drawn up to any point on the side of the building, so as to 75 carry the escape-car to any window or other point where imperiled persons may be, or to which it is desired to carry a fireman, hose, ladder, or any other person or thing, as clearly indicated by full and dotted lines in Fig. 2. 80

85 A cord or chain, *p*, may be attached to the car *o*, to enable it to be controlled by a person on the sidewalk or ground, in order to prevent said car from catching upon window casings or trimmings, or other projections 90 from the building.

95 Swiveling the supports for the lower pulleys upon their fixed supports enables persons on the ground drawing on the ends of rope *n* to move out on a line parallel with the face or side of the building, or at right angles thereto, as may be most convenient or safest.

If fibrous material is used for the ropes and car of the apparatus, it is designed that they shall be so treated as to render them practically fire-proof. In most instances it may be preferable to have the parts constituting a 100

permanent fixture to the building composed of metal.

With this exceedingly simple contrivance it will be seen that an entirely efficient fire-escape is provided, and one that may be readily operated by persons on the ground or sidewalk to rescue panic-stricken and imperiled persons in the burning building who may have so far lost their presence of mind as not to be able to manipulate other means of escape that may be within their reach.

It is designed that an escape-car, *o*, and rope *n* may be placed in possession of the fire-department, the janitor of the building, or other persons who can readily be called in case of emergency.

It is to be observed that the parts of the device that are to constitute permanent fixtures to the building are not of an unsightly character, that they are readily attached, and that the whole is exceedingly economic of construction and application and easy of use.

As many pulleys *b* *h* and ropes or chains *l* may be employed as may be thought necessary or desirable.

It is obvious that changes may be made in the form and arrangement of parts constituting my improvements without departing from the nature or spirit of the invention.

30 What I claim is—

1. As an improvement in fire-escapes, the upper and lower sheaves and pulleys attached to the front wall of a building, the two endless ropes or chains passed each around an

upper and lower pulley, and the car or vehicle having chains or cables designed to be connected to said endless ropes or chains at their outer ends, substantially as described, whereby said car or vehicle can be raised or moved to the desired point between said endless ropes or chains, as stated.

2. A building having its outer wall provided with a sheave or pulley at or near the roof or top and a similar sheave or pulley at or near the ground, and an endless rope or chain 45 passing over said pulleys, the bearing for the lower pulley being swiveled in its support, as set forth.

3. The herein-described improvement in fire-escapes, consisting of the upper and lower 50 sheaves and pulleys attached to the outer wall of a building near the ends thereof, the endless ropes or chains passed over the respective upper and lower pulleys and having hooks or attaching devices, the car or vehicle, 55 and the chains or cables secured thereto and designed to be connected at their outer ends to said hooks or attaching devices, substantially as described.

In testimony whereof I have signed my name 60 to this specification, in the presence of two subscribing witnesses, this 25th day of April, A. D. 1888.

CHARLES A. LUCE.
